Primary Examiner — George D Kirschbaum*Assistant Examiner* — Natasha Vujcic(74) *Attorney, Agent, or Firm* — Gottlieb, Rackman & Reisman P.C.(57) **CLAIM**

The ornamental design for a single bar hanger for a lighting system, as shown and described.

DESCRIPTION

FIG. 1 is a perspective view of the single bar hanger for a lighting system showing my new design;

FIG. 2 is a top plan view thereof;

FIG. 3 is a front elevational view thereof;

FIG. 4 is a right side elevational view thereof, the left side being a mirror image;

FIG. 5 is a rear elevational view thereof; and,

FIG. 6 is a bottom plan view thereof.

The broken lines in the drawings are included for the purpose of illustrating portions of the article that form no part of the claimed design.
